United States Patent

Des. 236,758
Patented Sept. 9, 1975

236,758

LUGGAGE

Pasquale R. Sollazzi, Newark, Del., assignor to Rapid-American Corporation, New York, N.Y.

Filed Apr. 30, 1973, Ser. No. 355,383

Term of patent 14 years

Int. Cl. D3—01

U.S. Cl. D87—5 F

FIG. 1

FIG. 2

FIG. 3

FIG. 4

FIG. 5

FIG. 1 is a front, top and left side prospective view of luggage showing my new design;

FIG. 2 is a rear elevational view;

FIG. 3 is a right side elevational view, the left side being a mirror image thereof;

FIG. 4 is a top plan view; and

FIG. 5 is a bottom plan view.

I claim:

The ornamental design for luggage, substantially as shown and described.
